Specification of Letters Patent.

Patented Nov. 9, 1920.

Application filed January 26, 1920. Serial No. 354,231.

To all whom it may concern:

Be it known that I, DAVID C. WILLIAMS, a citizen of the United States, and a resident of Arlington, in the county of Middlesex and State of Massachusetts, have invented a new and useful Improvement in Cabinets, of which the following is a specification.

My invention relates to cabinets and 10 more especially to cabinets of the talking-machine type. The object of my invention is to provide a cabinet that may be assembled quickly and accurately so as greatly to reduce the cost of the same.

15 It is a matter of experience that three-compartment talking-machine cabinets of the prior art require from four to five hours of skilled labor for assembling the parts thereof, whereas I have demonstrated that 20 the cabinet which constitutes the subject matter of the present invention may be assembled by unskilled labor in less than fifteen minutes, thus effecting a saving of between four and five dollars.

25 My invention comprises sectional posts which are formed with mathematical accuracy on a turning lathe, each section of each post being connected to its adjacent section by suitable attaching means, such 30 for example, as dowel screws. Horizontal partitions are arranged between each pair of adjacent sections, the surfaces of which are normal to the axis of the post, so that 35 said partitions will automatically be in absolute parallelism. Side plates forming the several compartments are arranged between the horizontal partitions and the corresponding sections of the posts, said partitions and posts preferably being grooved 40 to receive said plates.

One embodiment of my invention that has given good results in practice is shown in the accompanying drawings, although it will be understood that various modifications 45 in the precise details illustrated may be made without departing from the scope of my invention as set forth in the appended claims.

In the drawings—

50 Figure 1 is a front elevation of a talking-machine cabinet constructed in accordance with my invention. Fig. 2 is a longitudinal central section of the same. Fig. 3 is a horizontal section of the sound chamber taken on the line 3—3 of Fig. 2. Fig. 4

is a horizontal section of the record compartment taken on the line 4—4 of Fig. 2. Fig. 5 is a vertical section on an enlarged scale taken on the line 5—5 of Fig. 3. Fig. 6 is a fragmentary horizontal section taken 60 on the line 6—6 of Fig. 5. Fig. 7 is a fragmentary horizontal section taken on the line 7—7 of Fig. 5.

In the particular drawings selected for more fully disclosing the principle of my 65 invention 1 represents the record compartment of a talking-machine cabinet, 2 the sound chamber and 3 the turn-table compartment. Arranged at the four corners of the cabinet are posts accurately formed 70 on a turning lathe preferably by means of a revolving pattern in a manner well understood by those skilled in the art of wood work. Each post comprises several sections, shown in the present instance at 4, 5 75 and 6, although it will be understood of course that I do not limit myself to any particular number.

One member of each pair of sections is bored axially to receive a reduced axial 80 portion of the coöperating section. In the present instance the upper ends of the sections 4 and 5 are bored and the lower ends of the sections 5 and 6 are provided with reduced axial portions 5' and 6', respectively, although it will be clear that this arrangement might be reversed. The reduced axial portions 5', 6' are longer than the bores in which they are received so as to provide a space between each pair of 90 sections for the horizontal partitions 7, 8.

Each partition is bored near its corners to receive one of the reduced portions 5', 6', as shown at 9, 10.

The posts are provided with longitudinal 95 grooves 11, 12 arranged ninety degrees apart for receiving the vertical edges of the side plates 13. The horizontal partition 7 is provided with grooves 14 on its upper surface for receiving the lower edges 100 of the side plates, while the partition 8 is provided with similar grooves on both surfaces for receiving the upper edges of the plates 13 and the lower edges of the plates 15. In like manner the horizontal 105 partition 16 is grooved to receive the upper edges of the plate 15.

In order to connect each pair of post sections together I prefer to use dowel screws 110 17, one end of which is threaded into the

reduced portion of one of the post sections, and the other screwed into the coöperating section by turning the other section until the partitions are firmly clamped between the two and the longitudinal grooves 11, 12 are in proper position.

In assembling the cabinet the lowermost sections or legs 4 will first be arranged in position, the partition 7 placed thereon and clamped in position by the sections 5. The side plates are then inserted in the grooves 14 of the partition 7 and the grooves 11, 12 of the sections 5, the upper partition 8 placed in position and clamped by means of the uppermost sections 6. The side plates 15 are then inserted in the grooves which receive the same and the top partition or plate 16 is attached to the section 6 by the screws 18 or other suitable means.

20 Inasmuch as the parts making up my improved cabinet are all formed by machinery and no particular skill is required to assemble the same, it will be obvious that the cost of assembling such cabinet is much less than 25 where the methods now in vogue are pursued.

Having thus described an illustrative embodiment of my invention, without however limiting the same to the details thereof, 30 what I claim and desire to secure by Letters Patent of the United States is:

1. A talking-machine cabinet, comprising four posts each having three sections, the lowermost section of each post being axially bored to receive a reduced axial portion of the section next above and the middle section of each post being axially bored to receive a reduced axial portion of the uppermost section, dowel screws connecting each 35 section of each post with its adjacent section, horizontal partitions between each pair of sections of said posts, the said reduced axial portions of said sections of said posts

passing through holes near the corners of said partitions, and side plates fitting into 45 grooves in said posts and partitions.

2. A talking-machine cabinet, comprising four posts each having three sections, one end of the lowermost and middle sections of each post being axially bored to receive a 50 reduced axial portion of the adjacent section, dowel screws connecting each section of each post with its adjacent section, horizontal partitions between each pair of sections of said posts, the reduced axial portions of said 55 sections of said posts passing through holes near the corners of said partitions and side plates fitting into grooves in said posts and partitions.

3. A cabinet, comprising sectional posts, 60 one end of a section of each post being axially bored to receive a reduced axial portion of the adjacent section, means connecting each section of each post with its adjacent section, horizontal partitions between 65 each pair of sections of said posts, said reduced axial portion passing through holes near the corners of said partitions, and side plates coöperating with said posts and partitions.

4. A talking-machine cabinet, comprising four posts each having three sections, one end of the lowermost and middle sections of each post being axially bored to receive a 70 reduced axial portion of the adjacent section, means connecting each section of each post with its adjacent section, horizontal partitions between each pair of sections of said posts, the reduced axial portions of said 75 posts passing through holes near the corners of said partitions and side plates fitting into 80 grooves in said posts and partitions.

In testimony whereof, I have hereunto subscribed my name this 21st day of January, 1920.

DAVID C. WILLIAMS.
